UNITED STATES PATENT OFFICE.

JOHN KROPACZ, OF CALGARY, ALBERTA, CANADA, ASSIGNOR OF ONE-THIRD TO JOSEPH JAKUBECZ, OF CALGARY, ALBERTA, CANADA.

RAIL-SUPPORT.

1,328,002.

Specification of Letters Patent. Patented Jan. 13, 1920.

Application filed April 14, 1919. Serial No. 289,800.

To all whom it may concern:

Be it known that I, JOHN KROPACZ, a citizen of Poland, residing at Calgary, in the Province of Alberta and Dominion of Canada, have invented certain new and useful Improvements in Rail-Supports, of which the following is a specification.

The primary object of the invention is to provide a rail support of any length desired whereby a track may be elevated above the ties and firmly secured to the ties, the structure possessing great strength and being easy to manufacture.

A further object of the invention is to provide a supporting and securing means for rails adaptable for temporary tracks and readily laid in any lengths desired upon the road-bed for detachably mounting rails thereon, provision being made for also employing my invention for conduit purposes.

With these general objects in view, the invention will be fully described in connection with the accompanying drawings and in which like reference characters designate corresponding parts throughout the several views.

In the drawings,

Figure 1 is a vertical transverse sectional view through a portion of track embodying my invention,

Fig. 2 is a top plan view thereof,

Fig. 3 is a vertical longitudinal sectional view taken upon line III—III of Fig. 2,

Figs. 4 and 5 are sectional views taken upon lines IV—IV and V—V respectively of Fig. 1,

Fig. 6 is a perspective view of one end of a supporting member formed after my invention, and

Fig. 7 is a perspective view of the complementally formed opposite end of the supporting section.

Referring more in detail to the drawings my invention broadly consists of hollow supporting sections 10 trapezoidal in cross section, preferably formed of metal with complemental open ends for laying in jointed relations adapted for the seating reception of railway rails 11 thereon.

The supporting sections 10 have a base

or bottom 12 cut-away at one side as at 13 adjacent the inclined side 14 which is of greater width and obliquity than the opposite side 15 of the member 10.

A longitudinal rib 16 beneath the bottom 12 of the member 10 at the opposite side thereof from the cut-away portion 13 is adapted for anchoring the supporting member either in the ground or preferably upon a transverse tie 17 with the rib 16 positioned in a transverse groove 18 of said tie. When positioned in this manner, the portion thereof having the inclined side 14 is outwardly of the adjacent end of the tie 17 so that when the track is assembled, the inclined sides 14 will extend along the outer sides of the track for bracing the entire construction. One end of the supporting member 10 as illustrated in Fig. 6 of the drawings, has an upright post 19 acting as a brace and also projecting from the end of the member 10 adapted for reception within corresponding notches 20 in the top and bottom of the adjacent section.

It will be understood that a cut out portion 13 is provided at each end of the supporting member 10 at the side thereof adjacent the inclined side 14 and each member 10 having its opposite ends complementally formed by means of a post 19 and notches 20. It will be understood that the members may be positioned together for any desired length.

The ties 17 are transversely positioned upon the road-bed suitably spaced apart in the usual manner and the supporting members 10 are positioned in parallelism across the ties 17 and in interlocked relations as best illustrated in Fig. 2 of the drawings. The cut-away portions 13 of the bottom 12 are provided for convenience in mounting a connecting plate 21 upon bolts 22 carried by the tie 17 and projecting through perforations 23 in the bottom 12 adjacent said cut-away portions. Lock nuts 24 are placed upon the bolts 22 thereby securing the plate 21 in position with the supporting members 10 connected together. This operation is effected before the ground-work of the road-bed has been filled in at the outer sides of

the track, the cut-away portions 13 being closed when the invention is fully assembled.

The rails 11 are mounted longitudinally upon the top 25 of the members 10 adjacent 5 a longitudinal flange 26 at the outer side of the top, while spikes 27 are positioned upright through openings 28 in the top 25 for engaging over the base flanges 29 of the rail 10 and securing the rail in position. 10 Keys 30 are slidably mounted transversely through the supporting member 10 through slots 31 and 32 in the opposite sides 15 and 14 thereof respectively, the key 30 being tapered to conform to the size of said slots, 15 with the slot 31 at the inner side of the track of greater length than the outer slot 32.

The keys 30 are extended through the members 10 from the inner side thereof, that is through the slots 31 and are passed 20 through perforations 33 in the spikes 27 while a transverse cotter 34 is positioned through the outer end of each key 30 outwardly of the side 14 thereof. The members 10 may be bonded if desired by conductors 35 connected to the hooks 36 provided within each member 10 adjacent its opposite ends, while a conduit 37 or wire cable may be strung through the interior 25 of the continuously arranged supporting members 10 by the employment of loops 38 carried by the opposite sides 14 and 15 thereof.

Assembling the parts is accomplished by causing an interlocking connection between 35 adjacent rail ends seated on the tie 17, the posts 19 fitting in vertically alined sockets 20 and with the bolts 22 carried by the ties 21 extending upwardly through the openings 23 in the bases 12 of the members 10. When 40 so arranged, the bottom ribs 16 are seated in the tie recess therefor and the inclined sides 14 project outwardly of the ends of the tie with the adjacent earth beneath the sides 14 removed to permit access to the interior 45 of the members 10 through the medium of the enlarged registering openings 13. The plates 21 are then placed upon the bolts as illustrated in Fig. 1 and retained by fastening nuts 24, earth then being filled in adjacent the overhanging side 14 effectively to seal the interior of the members 10 and prevent access to the securing elements above 50 described. After the rails 11 have been positioned upon upper walls 25 of the members 10 with one edge of the base engaging the ridge 26, the bolts 27 are lowered into position through the openings 28 shown in Fig. 2 and retained by the keys 30 passing 55 through alined openings in the side walls 60 of the members 10 and through openings in the spikes 27 with cotters 34 received in the similar projecting ends thereof as shown in Fig. 1.

The invention is also serviceable in providing protecting means for conduits and

wires and is serviceable where a temporary track is desired, that can be readily disassembled for changing its location in an expeditious manner.

What I claim as new is:

1. A device of the class described comprising a hollow trapezoidal supporting member with open opposite ends, one of said ends having upper and lower notches, a strengthening post projecting from the opposite end adapted for fitting within the notches of the adjacent supporting member when in end to end formation, and a longitudinal flange adjacent the outer side of the top of each supporting member. 70 75

2. A device of the class described comprising hollow supporting members having complementally formed ends adapted for interengagement when the members are positioned for use, depending ribs upon said members adapted for engaging the road-bed adjacent the inner sides of the members, flanges at the outer side of the members on the top thereof, and holding means within the members upon the opposite sides thereof 80 85 adapted for receiving continuous line wires extending through the members.

3. A device of the class described comprising hollow open-ended supporting members trapezoidal in cross section, the open ends 95 having cut-away portions at each end adjacent the outer side thereof and with top and bottom notches at one end of the member, an upright strengthening post carried by the correspondingly opposite end of the member adapted for interlocked reception within the notches of the adjacently positioned member when assembled, and an anchoring rib carried by the bottom of the supporting member adjacent the inner side thereof. 100 105

4. A device of the class described comprising hollow open-ended supporting members trapezoidal in cross section, the open ends having cut-away portions at each end adjacent the outer side thereof and with top 110 and bottom notches at one end of the member, an upright strengthening post carried by the correspondingly opposite end of the member adapted for interlocked reception within the notches of the adjacently positioned member when assembled, and an anchoring rib carried by the bottom of the supporting member adjacent the inner side thereof, the sides of the members opposite the bottom ribs extending outwardly to overlie the ground adjacent thereto and prevent tampering with the interior of said members. 115 120

5. A device of the class described comprising hollow members, interlocking connections between adjacent ends, locking members positively connecting the ends together, the bottoms of said members having openings formed therein and with the side walls of the members adjacent the openings inclined out- 125 130

wardly to overlie same and to prevent tampering with said locking members when the members are assembled in operative position.

6. A device of the class described comprising hollow members, interlocking connections between adjacent ends, locking members connecting the ends together, the

bottom walls of said members having openings formed therein spaced inwardly of the adjacent side walls to permit access to said locking means during the assembling of said members. 10

In testimony whereof I affix my signature.
JOHN KROPACZ.
